UNITED STATES PATENT OFFICE.

NICK G. STAR, OF CORSICA, SOUTH DAKOTA.

AEROPLANE.

1,414,314.

Specification of Letters Patent. Patented Apr. 25, 1922.

Application filed August 28, 1920. Serial No. 406,690.

To all whom it may concern:

Be it known that I, NICK G. STAR, a citizen of the United States, residing at Corsica, in the county of Douglas and State of South Dakota, have invented new and useful Improvements in Aeroplanes, of which the following is a specification.

This invention relates to improvements in aeroplanes, the principal object of the invention being to provide a plurality of propellers with means for moving them into vertical position to raise the aeroplane off the ground and then move them into a horizontal position to drive the aeroplane horizontally through the air.

Another object of the invention is to provide means for adjusting the main propeller blades to any desired pitch to suit the condition of the air or to set them at such a pitch that the propeller will have a reverse action to act as a brake for the machine or to reverse its movement.

Still another object of the invention is to provide means whereby the main propeller blades may be adjusted and the other propellers moved to either horizontal or vertical position by manually operated means located adjacent the driver's seat.

This invention also consists in certain other features of construction and in the combination and arrangement of the several parts, to be hereinafter fully described, illustrated in the accompanying drawings and specifically pointed out in the appended claims.

In describing my invention in detail, references will be had to the accompanying drawings wherein like characters denote like or corresponding parts throughout the several views, and in which:

Figure 1 is a plan view of the invention.

Figure 2 is a side view.

Figure 3 is an enlarged sectional view through the supporting means for one of the swinging propellers.

Figure 4 is an elevation of one of the supporting means.

Figure 5 is an enlarged sectional view showing the means for adjusting the main propeller blades.

Figure 6 is a section on line 6—6 of Figure 5.

Figures 7 and 8 are detail views showing the connections between the hand levers and the different parts to be actuated thereby.

In these views 1 indicates the fuselage of

the aeroplane and 2 the planes thereof, these parts being arranged in any desired manner. A framework 3 is suitably connected with the planes and fuselage and this frame supports a plurality of brackets 4 in which the framework for the swinging propellers are supported. Each of these swinging propellers consists of an oil tight casing 5 which is provided with the hollow bearings 6 which engage openings formed in the bracket so that said casing is swingingly supported in the bracket. An open framework 7 is secured to the top of the casing and journaled in this framework and said top is the propeller shaft 8, to the outer end of which are connected the propeller blades 9. This shaft 8 is suitably journaled in the top of the casing and has its end extending into said casing and this end carries the beveled gear 10 which meshes with a gear 11 carried by the shaft 12 which passes through the hollow bearings 6 of the housing and is suitably journaled therein. These parts are provided with suitable packing means for preventing the oil within the casing from escaping.

As will be seen the propeller supporting frames are arranged in pairs with a shaft 12 for each pair, though one of the shafts engages one of these pairs. It will of course be understood, however, that these propeller supporting frames and the shafts may be arranged in any desired manner. These shafts 12 extend transversely across the aeroplane and adjacent each of the supporting frames I provide a universal joint 13 for permitting a certain amount of movement of the outer parts of each shaft. The shafts are connected with each other by the longitudinally extending shafts 14 and the gears 15, said gears being enclosed in casings 16 so that said gears may rotate in lubricant. These shafts 14 are also provided with universal joints 14'. The long shaft 12' which engages the two pairs of propeller supporting frames carries the gear 17 which meshes with the gear 18 on one of the shafts 14 and with a gear 19 which is located on the clutch shaft 20, these gears being located in the housing or casing 21. This shaft 20 is adapted to be connected with the shaft of the engine 22 by the clutch 23. Thus when the clutch is moved into operative position all the transverse shafts will be rotated so as to drive the propellers 9. The clutch is actuated from a point adjacent the driver's

seat by the hand lever 24 and the connecting links 25.

The means for moving the propeller supporting frames into horizontal or vertical positions comprises a transversely arranged shaft 26 which is provided with the arms 27, said arms being connected with the brackets 28, which are secured to the propeller supporting frames, by the links 29. Thus 10 when the shaft 26 is rocked said supporting frames will be raised and lowered to vertical and horizontal positions so that the propellers may be used for raising the aeroplane or for driving the same horizontally. This 15 shaft 26 is provided with a gear wheel 30 which meshes with a wheel 31 located on a short shaft 32 mounted in the fuselage adjacent the driver's seat. This shaft is provided with a hand wheel 33 by means 20 of which it may be rotated. This shaft is also provided with a brake drum 34 the brake band 35 of which is connected by the links 36 with the hand lever 37 so that after the wheel is turned to position the 25 propeller frames the brake can be applied to hold said frames in adjusted position.

The main propeller comprises the two blades 38 and the hub 39, said hub being connected with the engine shaft in the usual 30 manner. This hub is provided with a chamber 40 and the stems 41 of the blades are rotatably mounted in the hub and project within this chamber and the ends of these 35 stems carry the small gears 41' which are engaged by the rack bars 42 which are slidably mounted in the hub and have portions extending therefrom. These extending portions of the rack bars are connected by the pinions 43 with the collar 44, slidably 40 mounted in a part of the hub and rotating with said hub. This collar is provided with an annular groove in which is located a ring member 45 which is connected with the yoke 46. Ball bearings 47 are placed between the 45 ring member 45 and the walls of the groove. A lever 48 is pivoted intermediate its ends to the bracket 49 and one end of this lever is connected with the yoke 46 and its other end is connected with the rod 50 which is 50 connected with the hand lever 51. It will thus be seen that by manipulating the hand lever the collar will be moved on the inner part of the hub to reciprocate the rack bars so as to rotate the pinions 41 and thus adjust 55 the pitch of the blades 38. By this arrangement of parts the pitch of the main propeller blades may be adjusted to suit the condition of the air or they may be so adjusted as to

have a reverse action on the aeroplane to check the same or to cause it to travel in a 60 reverse direction. By swinging the propeller supporting frames into a vertical position and revolving these propellers the aeroplane may be caused to rise in the air without the usual speeding along the ground 65 and then gradually rising. When the aeroplane reaches the desired height the propellers may be swung into a horizontal position again and then used to drive the aeroplane horizontally through the air. 70

It is thought from the foregoing description that the advantages and novel features of my invention will be readily apparent.

I desire it to be understood that I may make changes in the construction and in 75 the combination and arrangement of the several parts, provided that such changes fall within the scope of the appended claims.

What I claim is:—

1. In an aeroplane, a pair of brackets 80 forming a part of the framework thereof, a casing having a pair of hollow bearings which are rotatably supported by said brackets, a shaft passing through the hollow bearings and the casing, an open framework 85 supported by the casing, a propeller shaft journaled in said framework and extending into the casing, gears located in the casing for connecting the two shafts together, a propeller on the propeller shaft, a bracket 90 connected with the open framework and manually operated means connected with the bracket for moving the casing in its supporting brackets to move the propeller into vertical or horizontal position. 95

2. In an aeroplane, a plurality of pairs of brackets forming part of the framework thereof, an oil tight casing having hollow bearings which are rotatably mounted in each pair of brackets, a plurality of transverse shafts extending through the hollow bearings and the casing, means for rotating said shafts, an open framework supported by each casing, a propeller shaft journaled in each open framework and extending into 100 the casing, gears in each casing for connecting the propeller shaft with its drive shaft, a bracket connected with each open framework and manually operated means connected with each bracket for moving the 105 parts to cause the casings to rock in the brackets to move the propellers into horizontal or vertical position. 110

In testimony whereof I affix my signature.

NICK G. STAR.
